UNITED STATES PATENT OFFICE.

LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY.

WATER HEAD.

Application filed April 3, 1924. Serial No. 704,010.

To all whom it may concern:

Be it known that I, LEWIS C. BAYLES, a citizen of the United States, and a resident of Easton, county of Northampton, State of Pennsylvania, have invented a certain Water Head, of which the following is a specification, accompanied by drawings.

This invention relates to rock drills of the hammer type, but more particularly to a water head for stope drills in which cleansing liquid is introduced into the hollow drill steel through the anvil block. Rock drills as they are ordinarily manufactured are provided with a liquid cleansing tube which is connected to the back head and extends centrally through the drill and into the hollow drill steel, for supplying cleansing liquid to the drilled hole, in order to eliminate dust and efficiently removing the cuttings. There are some localities where rock drills are used, in which the water, which is ordinarily used for cleansing purposes, contains acids which are injurious to the operative parts of the drills and which have a tendency in other ways to effect their efficient operation. It is therefore necessary in these places to introduce water into the drill steel through the front end parts of the machine, usually through the anvil block. In view of the fact that it is practically impossible to pack the anvil block in order to prevent the escape of liquid between the anvil block and drill steel, water collects in front of the anvil block and forms a cushion, which materially effects efficient drilling.

In accordance with the present invention, a chamber having expandable or resilient walls, is located in the front head, so that as the anvil block and drill steel are advanced and force the water in a radial direction, the resilient or expandable walls will give away and thereby eliminate the liquid cushion. This invention is particularly applicable to stope drills where there is a tendency for the cleansing liquid to run down the drill steel and enter the operative parts of the machine, and by means of this invention, the liquid which is bound to collect in front of the anvil block, does not in any way reduce the drilling.

The objects of the present invention are

to prevent the creation of a liquid cushion in a rock drill between the anvil block and the front head.

Another object of the invention is to maintain a constant clearance volume in the chamber into which the drill steel and anvil block extend, when the anvil block and steel are advanced by the percussive blows of the hammer piston.

Further objects of the invention will hereinafter appear and the invention is shown in one of its preferred forms in the accompanying drawings, in which—

Figure 1 is a vertical sectional view of the forward end of a stope drill embodying the present invention,

Figure 2 is a view similar to Figure 1, with the drill turned at right angles and showing the operation of the expandable chamber as the anvil block and the steel are advanced, and

Figure 3 is a perspective view of the resilient annular ring.

Referring to the drawings, A designates the cylinder of a fluid actuated stope drill, which is separated from the front head B by a front cylinder bushing C. The cylinder A, front cylinder bushing C and front head B are connected together by the usual spring pressed side bolts D and the hollow drill steel E is adapted to extend into the front head B for receiving the impact blows of the fluid actuated hammer piston F through the medium of the anvil block G. In this instance, a renewable bushing H is located in the forward end of the front head B and is held in place by a suitable pin or key J.

In accordance with the present invention, the front head B is formed with an annular chamber K adjacent its rearward end, and the drill steel E is adapted to extend a slight distance into the forward end of the chamber K. In this instance, the anvil block G is formed with a passage L, which is adapted to communicate with the passage in the hollow drill steel and in order to supply cleansing liquid to the passage L a passage O is formed in the front cylinder bushing C. A water inlet connection P is suitably connected to the front cylinder bushing C and

a bushing Q is located in the passage O and is preferably held in place against the anvil block G by a coil spring R which bears against a washer S. In this manner, the bushing Q is held against the anvil block G to enable cleansing liquid from the inlet connection P to pass through the bushing Q and into the passage L in the anvil block and thence into the hollow drill steel E. Flattened portions T are preferably formed on the neck U of the anvil block G in order to prevent the anvil block from turning, so that the passage L will at all times register with the sleeve or bushing Q. In this instance, a counter bore V is preferably formed in the bushing C adjacent one end of the neck U of the anvil block, to enable the anvil block to seat as tightly as possible in the bore of the bushing C. It is to be understood that cleansing liquid may be introduced into the anvil block G by any suitable means, and only one means is shown on the drawing for illustrative purposes, and it is not desired to limit this invention to the particular means shown, for supplying liquid to the anvil block.

In this instance, an annular groove W surrounds the bushing Q and preferably communicates with an atmospheric vent X by means of a port Y, and an annular groove Z preferably surrounds the anvil block G and also communicates with the atmospheric vent X. In this manner, any liquid which escapes between the anvil block G and the bushing C and from between the bushing Q and the bushing C, will pass to atmosphere through the vent X and will not interfere with the efficient operation of the anvil block G.

In view of the fact that it is practically impossible to maintain a fluid tight connection between the head of the anvil block G and the drill steel E, because of the constant relative movement between the drill steel and the anvil block, a portion of the cleansing liquid will collect in the chamber K. If no means are provided for maintaining a constant clearance volume in the chamber K, as the anvil block and steel are advanced by means of the hammer piston F, a liquid cushion will be created in the chamber K and efficient drilling will be impaired. Therefore, in order to maintain a constant clearance volume in the chamber K, as the anvil block G and steel E are advanced, a resilient ring *a* is located in the chamber K and forms a resilient annular wall for the chamber K. The ring *a*, which may be of rubber or other suitable material, comprises the body portion *b* and external annular flanges *c* and *d*. When the anvil block G and steel E are advanced, the liquid in the chamber K will be displaced radially as indicated in Figure 2, without being discharged from the front head B. An atmos-

pheric vent *e* in the front head B enables atmospheric pressure to be maintained against the body portion *b* of the ring *a*.

By providing the recess K with a resilient or expandable wall, the danger of the liquid cushion in the chamber is obviated and efficient drilling may be obtained.

I claim:

1. In a head for rock drills for feeding cleansing fluid to the drilled hole, an expandable water chamber, a drill steel extending into one end of the chamber, and an anvil block extending into the other end of said chamber. 75

2. A head for rock drills for feeding cleansing fluid to the drilled hole, said head having an expandable chamber into which liquid is introduced and adapted to permit the displacement of a portion of said liquid without discharging said liquid from the head, a drill steel extending into one end of the chamber, and an anvil block extending into the other end of said chamber. 80

3. A head for rock drills for feeding cleansing fluid to the drilled hole, said head having an expandable chamber into which liquid is introduced, and adapted to maintain a substantially constant clearance volume therein, a drill steel extending into the forward end of said chamber, and an anvil block to reciprocate within said chamber for delivering blows against the drill steel. 90

4. In a front head for rock drills, a chamber capable of receiving cleansing liquid, an anvil block forming one side of said chamber, a drill steel extending into the opposite side of the chamber and abutting the anvil block, and a yielding side to the chamber so that the volume of said chamber may remain substantially constant when the anvil block and drill steel are moved forwardly in the chamber. 100

5. In a rock drill of the hammer type the combination of a front head having a chamber, a front cylinder bushing, a hollow drill steel adapted to extend into the forward end of said chamber, an anvil block having a head of larger cross sectional area than the said drill steel located in said bushing and extending into the rearward end of said chamber, means for supplying cleansing liquid through said anvil block to said drill steel and means in said front head for permitting the displacement of a portion of the liquid in said chamber in front of said anvil block without discharging said liquid from the front head. 110

6. In a rock drill of the hammer type, the combination of a front head having a chamber, a front cylinder bushing, a hollow drill steel adapted to extend into the forward end of said chamber, an anvil block having a head of larger cross sectional area than said drill steel located in said bush- 120

130

ing and extending into the rearward end of said chamber, means for supplying cleansing liquid through said anvil block to said drill steel, and means for maintaining a constant clearance volume in said chamber when said anvil block and steel are advanced.

7. In a rock drill of the hammer type, the combination of a front head having a 10 chamber, a front cylinder bushing, a hollow drill steel adapted to extend into the forward end of said chamber, an anvil block having a head of larger cross sectional area than said drill steel located in said bushing 15 and extending into the rearward end of said chamber, means for supplying cleansing liquid through said anvil block to said drill steel, and resilient means for maintaining a constant clearance volume in said chamber when said anvil block and steel are advanced.

8. In a rock drill of the hammer type, the combination of a front head having a 20 chamber, a front cylinder bushing, a hollow drill steel adapted to extend into the forward end of said chamber, an anvil block having a head of larger cross sectional area than said drill steel located in said bushing and extending into the rearward end 25 of said chamber, means for supplying cleansing liquid through said anvil block to said drill steel, and a resilient ring in said chamber for maintaining a constant

clearance volume in said chamber when said anvil block and steel are advanced. 35

9. In a rock drill of the hammer type, the combination of a front head having a chamber, a front cylinder bushing, a hollow drill steel adapted to extend into the forward end of said chamber, an anvil block 40 having a head of larger cross sectional area than said drill steel located in said bushing for supplying cleansing liquid through said anvil block to said drill steel, and an expandable wall for said chamber for maintaining a constant clearance volume in said chamber when said anvil block and steel 45 are advanced.

10. In a rock drill of the hammer type, the combination of a front head having 50 a chamber, a front cylinder bushing, a hollow drill steel adapted to extend into the forward end of said chamber, an anvil block having a head of larger cross sectional area than said drill steel located in said bushing and extending into the rearward end 55 of said chamber, means for supplying cleansing liquid through said anvil block to said drill steel, and a renewable expandable annular ring for said chamber for 60 maintaining a constant clearance volume in said chamber when said anvil block and steel are advanced.

In testimony whereof I have signed this specification.

LEWIS C. BAYLES.
